CUTLERY SHARPENER

Leo A. Hoek, Los Angeles, Calif.

Application January 2, 1951, Serial No. 204,049

7 Claims. (Cl. 51—102)

1

This invention relates to sharpening devices, and particularly to a machine having a rotating grinding wheel for knives, hatchets, and tools having similar forms of blades.

Grinding apparatus has been known and used, two forms being shown in U. S. Patents No. 1,756,710 and No. 2,052,837. The grinder of the present invention is especially adapted for sharpening cutlery of different shapes and sizes and the sharpening may be done by inexperienced operators with the same results as when done by experienced operators. The grinder embodies a knife guiding and positioning bracket which is adjustable both toward and away from the grinding wheel to accommodate various sized knives, and which is adjustable with respect to the surface of the wheel to obtain different angles on the blades being ground.

The machine is silent in operation and sharpens a blade in a few seconds, providing an edge which is proper for the type of tool being sharpened. It has few parts, is economical to build, and is particularly sturdy and rugged.

The principal object of the invention, therefore, is to facilitate the grinding and sharpening of cutlery.

Another object of the invention is to provide an improved grinder for cutlery.

A further object of the invention is to provide an improved grinding machine which is easily operated and adjustable for cutlery of different types and sizes.

Although the novel features which are believed to be characteristic of this invention will be pointed out with particularity in the appended claims, the manner of its organization and the mode of its operation will be better understood by referring to the following description, read in conjunction with the accompanying drawings, forming a part hereof, in which:

Fig. 1 is a plan view of a grinder embodying the invention with the cover partially removed.

Fig. 2 is a cross-sectional view taken along the line 2—2 of Fig. 1.

Fig. 3 is a cross-sectional view taken along the line 3—3 of Fig. 2.

Fig. 4 is an end elevational view of the cutlery holding and positioning bracket taken along the line 4—4 of Fig. 3.

Fig. 5 is a side view of the bracket of Fig. 4.

Fig. 6 is a plan view of a modification of the bracket of Figs. 1 to 5, inclusive, and

Fig. 7 is a cross-sectional view of the bracket modification shown in Fig. 6 and taken along the line 7—7 of Fig. 6.

2

Referring now to the drawings, in which the same numerals identify like elements, a horizontal base 5 has legs 6 with suction cup feet 7 at three points under the base. A cover 9 having latch end 10 which hooks in an opening 11, is held by thumb screw 12 when a slot in the cover is fitted over the screw. The cover may be in two parts, a smaller part 13 being removed from over the tool holding bracket when the machine is to be used.

Mounted in vertically extending studs 14, 15, 16, and 17 from the base 5, is a motor 19 on the shaft 20 of which is the hub 21 of a grinding wheel 22. Screw and nut combinations 23 hold the motor on the studs. The hub 21 is held on the shaft by set screw 24, and the wheel 22 is held in position by the nut 25. A switch 26 on the cover 9 controls the energizing and de-energizing of the motor 19, the wheel 22 being rotated in the normal way, the direction of rotation being as shown by the arrow in Fig. 3, which is against the edge of the blade being sharpened. A trough 27 is provided in the base to accommodate wheels of large sizes.

To position the blade of the knife or other tool properly, so that it is only necessary to move it across the rim of the wheel, the bracket shown generally at 28 is used. This bracket has an outer backing shoe 30 and an inner shoe 31 hinged on a pin 32 passing through parallel extending flanges from the lower portion of shoe 30, one flange being shown at 33. The shoe 30 has wing flanges 34 and 35, flange 34 having threaded therein one end of a carriage rod 36 and also has a drill hole therein in which a threaded bolt 37 is rotatable by finger knob 38. The rod 36 is slideable in two upright studs 39 and 40 from the base 5, stud 40 having a wide portion 41, in which bolt 37 is threaded. A coil tension spring 42 surrounds bolt 37 and abuts extension 41 and flange 34. Thus, by turning bolt 37, both shoes 30 and 31 are moved either toward or away from the rim of the wheel 22, the spring 42 moving the flange away from the wheel when the bolt 37 is backed off.

The other flange 35 has the end of a rod 43 threaded therein, and passing through a hole in the flange is a threaded bolt 44, on which is a hand nut 45 threadable thereon. The rod 43 is slideable on a stud 46 from the base 5, while the end of bolt 44 has a head 47, the bolt passing through the side flange from shoe 31. Thus, rotation of the nut 45 in one direction will draw the shoe 31 toward the shoe 30, and when the nut 45 is rotated in the reverse direction, a spring 49 on

the bolt 44 will separate the shoes. The shoes may thus be adjusted with respect to one another to accommodate cutlery of different thicknesses, while the position of the shoes is adjusted to position the blade edge at a point substantially on a horizontal plane through the axis of the wheel. This is the proper adjustment as shown by the edge of a portion of a blade 50 in Fig. 3. The blade is then simply drawn between the shoes first on one side, then the other, until the desired sharpness is obtained.

As shown plainly in Fig. 2, the wheel 22 has a beveled rim, and it is noted in Fig. 1 that the opposing surfaces of the shoes 30 and 31 are at the same angle. The edges of the blades, therefore, contact the flat surface of the wheel rim, which is the proper contact between the blade and wheel. If wheels with different bevels are used, shoes with different angles may be substituted for shoes 30 and 31. An angle of approximately ten degrees has been found desirable.

To obtain the correct position of and guide the blade against the wheel, the outer shoe 30 has a curved cut-out portion 52 and a substantially flat upper surface 53. The shoe 31 has a curved blade contacting surface and has a cut-out slot 51 therein to accommodate the wheel 22. It has been found that the shape and design of these shoes and their adjustability, as described above, permits beginners to sharpen blades expertly by 30 grinding.

To avoid shoe substitutions to obtain different holding angles for the blades, the shoes 55 and 56, which are hinged at 57, are similar in shape to shoes 30 and 31, but rotatable about a vertical axis passing through a screw 58, which holds the shoes on a carriage block 59. (See Figs. 6 and 7.) The carriage block is slideable toward and away from the wheel in the plane of the wheel in a rectangular groove or trough 61 in the base 60, which has the general form of the base 5. The block has an opening 62 therein, the rear portion 63 having a screw 64 with a finger knob 65 threaded therein, the screw being rotatable in a flange 66 of the base. Thus, turning of the screw 64 moves the shoes 55 and 56 toward and away from the wheel 22, as does screw 37 in the other figures. When the shoes are properly positioned, a clamp 68 on a bolt 69 is tightened by wing nut 70 on carriage 59. Thus, the edge of any blade may be positioned at any desired angle with respect to the rim surface of the wheel by simply loosening screw 58, rotating the shoes 55 and 56 to the desired angle, and then tightening screw 58. A bolt 72, with finger knob 73 and spring 74, is provided for shoes 55 and 56 to adjust their inner surfaces with respect to one another to accommodate blades of different thicknesses.

With the modification shown in Figs. 6 and 7, the shoes 55 and 56 may be quickly adjusted for a particular wheel and the sharpening accomplished quickly and expertly by inexperienced operators. A constant bevel will be ground on the blade at all points by simply drawing the blade across the wheel.

I claim:

1. A grinding machine comprising a base, a motor mounted on said base, a grinding wheel rotatable by said motor, said wheel having a rim, a blade guide mounted on said base adjacent said rim of said wheel, said blade guide including a pair of shoes, one shoe being closer to said wheel than the other shoe, means joining said shoes for adjusting their inner surfaces with respect

to one another, and means for adjusting both of said shoes simultaneously as a unit toward and away from said rim of said wheel in the direction of the plane of one side surface of said 5 wheel, the shoe farthest from said grinding wheel having its surface facing said grinding wheel curved at the central portion thereof and said other shoe having a slot therein to permit the passage of the rim of said grinding wheel there-through, and a curved surface facing said first mentioned shoe.

2. A grinding machine comprising a base, a motor mounted on said base, a grinding wheel rotatable by said motor, said wheel having a rim, 15 a blade guide mounted on said base adjacent said rim of said wheel, said blade guide including a pair of shoes, one shoe being closer to said wheel than the other shoe, means joining said shoes for adjusting their inner surfaces with respect to one another, and means for adjusting both of said shoes simultaneously as a unit toward and away from said rim of said wheel in the direction of the plane of one side surface of said 20 wheel, said shoes being rotatable on a vertical axis passing between said shoes and perpendicular to the axis of rotation of said wheel to vary the inner surfaces of said shoes with respect to the surface of the rim of said wheel.

3. A cutlery sharpener having a grinding wheel 30 adapted to rotate against a blade to be sharpened, comprising a grinding wheel having a rim, a motor for rotating said wheel, a carriage, a pair of shoes mounted on said carriage and having opposing surfaces, screw means for simultaneously adjusting said shoes toward and away from said rim of said wheel, and screw means for adjusting the position of one of said shoes with respect to the other, said shoes being hinged together at the ends thereof, one shoe having a 35 concave inner surface and the other shoe being slotted to permit passage of said rim of said wheel therethrough.

4. A cutlery sharpener having a grinding wheel 45 adapted to rotate against a blade to be sharpened, comprising a grinding wheel having a rim, a motor for rotating said wheel, a carriage, a pair of shoes mounted on said carriage and having opposing surfaces, screw means for simultaneously adjusting said shoes toward and away from said rim of said wheel, and screw means 50 for adjusting the position of one of said shoes with respect to the other, means being provided for simultaneously rotating said surfaces of said shoes on an axis passing between said surfaces of said shoes and perpendicular to the axis of rotation of said wheel.

5. A blade guide and positioner for blades to be sharpened by a grinding wheel having a rim, 60 comprising a pair of shoes having opposing surfaces and their central planes substantially parallel, a portion of the opposing surface of one shoe being flat, and another portion of said surface being concave, the other shoe having its opposing surface convex, said other shoe being slotted to permit passage of said rim of said wheel therethrough, and means to hinge one end of one shoe to one end of said other shoe.

6. A blade guide and positioner in accordance 65 with claim 5, in which means are provided to adjust the opposing surfaces of said shoes with respect to one another, and means are provided to simultaneously move said shoes toward and away from said wheel.

7. A blade guide and positioner in accordance 70 with claim 6, in which further means are pro-

vided to simultaneously rotate said shoes on a vertical axis.

LEO A. HOEK.
